UNITED STATES PATENT OFFICE

HORACE D. STEVENS, OF AKRON, OHIO, ASSIGNOR TO THE FIRESTONE TIRE AND RUBBER COMPANY, OF AKRON, OHIO, A CORPORATION OF OHIO

GRINDING OR BUFFING MACHINE

Application filed August 6, 1927. Serial No. 211,203.

This invention relates to grinding or buffing machines and has particular reference to semi-automatic machines for grinding, buffing or polishing casters, rollers, rings or other 5 annular or disc-shaped objects.

The object of the invention is to devise semi-automatic means for accurately, speedily and safely grinding or polishing annular or disc-like objects. A further object is to 10 devise a machine comprising a traveling, abrasive belt, rotating buffing wheel, or the like, means for conveying and successively presenting annular objects to the belt or wheel to be buffed or ground, and means for 15 removing the finished objects from the conveying means.

The foregoing and other objects are obtained by the device illustrated in the accompanying drawings and described below. It 20 is to be understood that the invention is not limited to the specific embodiment thereof disclosed herein.

Of the accompanying drawings,

Figure 1 is a plan view of a machine embodying the principles of the invention;

Figure 2 is a rear elevation thereof;

Figure 3 is a plan detail of a portion of the machine as viewed from below;

Figure 4 is a side elevation of the machine 30 as viewed from the discharge side thereof;

Figure 5 is a vertical section taken on the line 5—5 of Figure 1; and

Figure 6 is a vertical section taken on the line 6—6 of Figure 1.

Referring to the drawings, 10 represents standards for supporting a table 11 carrying on its under surface the driving mechanism of the device as shown in Figure 3. Power is derived from a motor 12 mounted on 40 bracket 13 attached to the table, the shaft 14 of the motor having fixed thereto a pinion 15 meshing with a gear 16 to rotate shaft 17. A small sprocket 18 drives chain 19 which is trained over a large sprocket 20 fixed to 45 shaft 20^a journaled through the table, and pinion 21, turning with sprocket 20, meshes with gear 22 to rotate shaft 23 and the arm 24 attached to the upper end thereof at a reduced rate of speed.

50 On top of table 11, arm 24 carries on one

end an upwardly projecting roller 25 to engage a star cam 26 for intermittently rotating carriage wheel or turret 27 through a portion of a revolution, star cam 26 and wheel 27 being integrally formed and journaled about bearing 27^a through which shaft 20^a passes. Pivoted arms 28 mounted on wheel 27 each have a stud 29 on one end for holding the articles to be ground or buffed, while each of the other ends of the arms is yieldingly held 55 against a stop pin 30 by a spring 31 connected to arm 32, the latter being attached to shaft 33 which is journaled through wheel 27 and fixed in its respective arm 28. Reverse motion of wheel 27 is prevented by the action of leaf spring pawl 34 which engages behind ratchet teeth 35 on wheel 27 and forward rotary motion of the latter is arrested by a brake 36 yieldingly pressed against the outer periphery of the wheel when the end of arm 24 opposite roller 25 engages leaf spring 37 just as said roller is disengaged from the star cam, this position of arm 24 and leaf spring 37 being shown by dotted lines in Figure 1. Brake 36 and leaf spring 37 are connected to 60 a sleeve 38 pivoted on a stud shaft 39 adjustably mounted on table 11. Spring-pressed roller 40 snaps successively into recesses 41 to remove the finished objects from the conveying means.

The abrasive or buffing means illustrated in the drawings by a dotted line comprises a grinding or polishing belt 42 trained over pulleys 43 and 44. Pulley 43 is attached to shaft 17 which is journaled in bearing 45 and 65 is driven by gear 16 as previously noted. Pulley 44 is pivoted on lever arm 46 mounted to swing on stud shaft 47 so that belt 42 may be held under tension by a spring 48 stretched between lever arm 46 and a stud 49 mounted 70 in table 11. In order to resist pressure of the annular object 50 to be ground or polished, a spring-pressed roller 51 engages the back of the belt at the point of contact, maintaining a uniform pressure of the belt against the 75 object. The opposite side of the object 50 is contracted by a drive wheel 52 for rotating the object in a direction counter to the direction of belt 42. Drive wheel 52 is journaled on a stud shaft 53 carried by a bracket 54. 80

which is in turn clamped to the upper end of bearing 27^a. A gear 55 fixed on the upper end of shaft 20^a meshes with a gear 56 fixed to drive wheel 52 for rotating the latter in the direction indicated by the arrow in Figure 1.

5 A slightly tilted driven roller 57 is provided to engage the objects 50 for removing the latter from the studs when the grinding operation is finished. Shaft 58 carrying 10 roller 57 is journaled on an arm 59 clamped in a bracket 60 which is attached to the upper end of stud shaft 53, whereby arm 59 may be adjusted to tilt roller 57 at a slight vertical angle for raising object 50 off stud 29 when 15 roller 58 is rotated. A belt 61 trained over pulleys 62 and 63 attached to shafts 17 and 58, respectively, serves to rotate the take-off roller, and the latter with help of a guard 64 discharges the finished objects into a chute 20 65. A reamer or drill 66 may be mounted on the machine and driven from the drive thereof for cleaning or boring central apertures of the objects to be ground so that they will fit over studs 29.

25 In the operation of the machine, for grinding or buffing mold marks off rubber casters, for instance, the operator reams a central aperture in the casters and places one on each stud carried by the intermittently rotated 30 carriage wheel. The drive wheel 52 successively engages each caster, forcing it radially outwardly against the traveling abrasive belt for a short period of time and rotating the 35 caster in a direction opposite to that of the belt. As the finished caster passes on, it is engaged by the take-off roller which removes the caster from the stud and discharges it into the outlet chute.

40 The operation of the machine is thus entirely automatic with the exception of the step of placing the objects onto studs 29, and grinding or buffing is accurately and rapidly accomplished thereby with safety for the operator.

45 Modifications of the construction herein disclosed may be resorted to without departure from the scope of the invention as defined by the appended claims.

50 What is claimed is:—
1. A grinding or buffing machine comprising a conveyor wheel, studs carried by said conveyor wheel and adapted to have freely journaled thereon objects to be ground or buffed, a traveling abrasive element, means 55 for intermittently rotating said conveyor wheel to bring each object successively into engagement with said abrasive element, and means for rotating said objects on said studs in a direction counter to the direction of the 60 abrasive element.

2. In a machine of the class described, a 65 turret for conveying articles to be ground or buffed, means carried by said turret upon which said articles may be mounted and which are pivoted for movement transverse-

ly of the path of travel of said turret, a traveling abrasive element, and means for successively forcing the articles transversely of their path of travel to cause the periphery of said articles to come into engagement with said abrasive element.

3. In a machine of the class described, a device for conveying articles to be ground or buffed, means for mounting said articles on said device for movement transversely of the path of travel thereof, a traveling abrasive element, and a rotatable wheel for rotating and successively forcing the articles against said abrasive element and transversely of their path of travel.

HORACE D. STEVENS.
